UNITED STATES PATENT OFFICE

2,607,621

OFF-SPOT LOCATOR AND SPARE PICKUP
FOR BOWLING MACHINES

Thomas C. Pulvino, Rochester, N. Y.

Application December 8, 1949, Serial No. 131,874

7 Claims. (Cl. 294—88)

1

This invention comprises novel and useful improvements in bowling pin respotting devices, and more particularly pertains to a bowling pin pickup device.

An important object of this invention is to provide a bowling pin pickup device which will automatically retain a bowling pin thrust therein and selectively discharge a bowling pin therefrom.

Another object of this invention in accordance with the foregoing object, is to provide a bowling pin pickup device which will not damage the bowling pins, which is of simple construction yet durable and highly efficient for the purposes intended.

An important feature of this invention resides in the provision for a bowling pin pickup device having a unidirectionally yieldable bowling pin constriction therein.

Another important feature of this invention resides in the provision for means for selectively opening the constriction to discharge bowling pins therefrom.

Another feature of this invention resides in the provision for fingers having bifurcated pin embracing ends.

These, together with various ancillary objects and features are attained by this device, a preferred embodiment of which has been illustrated by way of example only in the accompanying drawings wherein:

Figure 1 is a perspective elevational view of the bowling pin pickup device shown engaging a bowling pin.

Figure 2 is a fragmentary elevational side view of the bowling pin pickup device, showing details of bowling pin engaging fingers.

Figure 3 is a fragmentary elevational top view of the bowling pin pickup device when engaging a bowling pin shown in section.

Figure 4 is a fragmentary top plan view of a bowling pin respotting board to which the bowling pin pickup device is to be attached.

In bowling, after the first ball has been rolled, all pins which have been knocked down, generally termed "deadwood," must be removed, and all pins remaining upright either in their original positions or laterally shifted therefrom, must remain in their newly acquired positions pending the rolling of the second ball.

In order to facilitate the removal of the deadwood there is generally provided a means for raising the upright pins, thereby permitting the deadwood to be swept off the alley, the pins then being replaced to the positions from which they were raised. For this purpose there is generally

2

provided a "respotting board" to which a bowling ball pickup device is attached for limited lateral movement relative thereto.

In operation, the bowling pins which remain upright after the first ball is rolled and which have shifted from their original position by reason of impact from the bowling ball or from another bowling pin, contact the bowling pin pickup device in such a manner as to laterally shift the pickup device relative to the respotting board thereby aligning the pickup device with the off-center bowling pin. The pickup device then engages the bowling pin so that when the respotting board is raised, the bowling pin is also raised, thereby permitting the deadwood to be swept away, after which the respotting board is again lowered and the pin discharged in the position from which it was raised.

Bowling pin pickup device

Referring now to the accompanying drawings wherein like numerals designate similar parts throughout the various views, the bowling pin pickup device, indicated generally by the numeral 10 and to which this invention relates, is shown in Figure 4 attached to a bowling pin respotting board 12.

In order to facilitate the shifting of the bowling pin pickup device 10 relative to the respotting board 12, the pickup device 10 is provided with a downwardly and outwardly flared member which is preferably of the form of a frusto-conical section 14, the upper portion of the frustum 14 receiving a sleeve 16 thereon, the sleeve being secured to the frustum 14 in any desired manner. If the bowling pin, indicated generally by the numeral 18, is "off-center" from its original position, the head of the bowling pin 18 will engage the frustum 14 and cause a lateral shifting thereof relative to the bowling pin respotting board 12, the lateral shifting being permitted by the means by which the pickup device is attached to the respotting board, which attachment is well known to those skilled in the art and forms no part of this invention.

Attached to the sleeve 16 in any suitable manner, as by the brackets 20 are radially disposed pin engaging fingers 22. The brackets 20 preferably have arcuate shaped legs 24 which embrace the sleeve 16 and are attached thereto by means of fasteners 26, together with outwardly extending parallel arms 28 between each pair of which are pivotally received, by means of the pivot pin 30 which is journaled in the arms 28, the bowling pin engaging fingers 22.

Secured to, in any desired manner such as by welding, and laterally spacing the rear portions of the arms 28, is a block 32. To the block 32 is fastened, as by the bolt 34 and washer 36, an arcuate resilient spring member 38 which slidably engages the finger 22 so as to yieldingly urge the latter downwardly. A detent pin 40 which is secured in, or formed as part of the finger 22 engages the upper portion of the arms 28 so as to limit downward movement of the fingers 22 to a preferably horizontal position.

A solenoid 42, of known construction, and having a plunger 44 reciprocably mounted within its core is provided, the plunger being yieldingly urged outwardly by a spring 46 or the like, which spring is secured to the outward end of the plunger 44. The solenoid 42 is attached to the arms 28 by a preferably U-shaped bracket 48 having longitudinal slots 50 in its upper portion, which slots receive the arms 28, apertures 52 being provided in the opposite ends of the U-shaped bracket to slidably receive and guide the plunger 44, the bolt 34 being received in the bracket 48 so as to support the latter from the arms 28.

The plunger 44 is provided, at its inner end, with an annular flange 52, which is rigidly secured to the plunger, a frusto-conical cap 54 being secured to and coaxial with the plunger 44 and flange 52. The cap 54 and flange 52 engage a projection 56 on the finger 22 so as to pivot the finger 22 upwardly and outwardly upon energization of the solenoid 42.

Electrical connectors 56 and 58 which are connected in an electrical circuit, not shown, and which forms no part of this invention, are provided for the solenoid 42, whereby the solenoid may be selectively actuated to disengage the fingers 22 from the bowling pin 18.

In operation, the pickup device 10 is lowered over the bowling pin 18, thereby causing a lateral shifting of the pickup device 10 relative to the board 12 as previously discussed, the bifurcated pin engaging extremities 60 of the fingers 22 contacting the rounded head 62 of the bowling pin 18, the fingers 22 being thereby pivoted upwardly and outwardly. As the neck 64 of the pin 18 is guidingly contacted by the extremities 60 of the fingers 22, the fingers 22 are urged downwardly by the springs 38, the inward ends of fingers being so positioned as to loosely receive the neck of the bowling pin therebetween. As the downward pivoting of the fingers 22 is limited by the pin 40 engaging the arm 28, the pin 18 will be raised as the pickup device 10 is raised, the head 62 of the pin 18 being too large to pass through the constriction formed by the fingers 22.

Release of the pin 18 is accomplished by first lowering the pickup device 10 and then energizing the solenoid 42 to thereby actuate the plunger 44 against the spring 46, the flange 52 of the plunger engaging the projection 56 of the fingers 22 to thereby upwardly pivot the fingers and disengage the pin 18 whereupon the pickup device 10 may be raised, leaving the pin 18 in substantially the position from which it was removed.

From the foregoing, it is believed that the construction and operation of the device will be readily understood and further explanation is believed to be unnecessary. However, since numerous modifications will readily occur to those skilled in the art after a consideration of the foregoing specification and accompanying

drawings, it is not desired to limit the invention to that shown and described but all suitable modifications may be resorted to falling within the scope of the appended claims.

Having described the invention what is claimed as new is:

1. In a movable bowling pin respotting board; a pickup device attached to said board for limited lateral movement relative thereto, said device comprising a frustum, a sleeve on said frustum, a unidirectionally yieldable constriction in said sleeve for receiving and retaining the upper portion of a bowling pin therein, said constriction including radially disposed vertically pivotal fingers, means attached to said fingers limiting downward pivotal movement thereof below a horizontal position, release means attached to said sleeve for selectively pivoting said fingers upwardly and outwardly to discharge a bowling pin from said constriction, said release means including a solenoid, a plunger operated by said solenoid, said plunger operatively engaging said fingers to positively release said constriction.

2. In a movable bowling pin respotting board; a pickup device attached to said board for limited lateral movement relative thereto, said device comprising a frustum, a sleeve on said frustum, a unidirectionally yieldable constriction in said sleeve for receiving and retaining the upper portion of a bowling pin therein, said constriction including radially disposed vertically pivotal fingers, means attached to said fingers limiting downward pivotal movement thereof, release means attached to said sleeve for selectively pivoting said fingers upwardly and outwardly to discharge a bowling pin from said constriction, said release means including a solenoid, a plunger operated by said solenoid, said solenoid having a flange thereon, a shoulder on lower portion of said finger, said flange engaging said shoulder upon actuation of said solenoid to positively release said constriction.

3. A bowling pin pickup device comprising a downwardly flared housing, a unidirectionally yieldable constriction on the upper end of said housing for receiving and retaining the upper end of a bowling pin, said constriction including a plurality of elongated fingers each having a bowling pin engaging end, arms on said housing vertically pivotally attaching said fingers adjacent the smaller end of said housing, said fingers extending radially inwardly of said housing and forming a constriction, pins on said fingers engaging said arms for supporting said fingers in a horizontally disposed position, said fingers being so constructed and arranged to vertically pivot upwardly when the head of a bowling pin is passed therethrough and pivot downwardly into a horizontally disposed position when the neck of a bowling pin is received between said fingers to prevent withdrawal of the pin from the pickup device, and means for selectively vertically pivoting said fingers into their bowling pin releasing position, said last-mentioned means including a solenoid disposed adjacent each of said fingers, a plunger actuated by each of said solenoids and each engaging one of said fingers to vertically pivot said fingers.

4. A bowling pin pickup device comprising a downwardly flared housing, a unidirectionally yieldable constriction on the upper end of said housing for receiving and retaining the upper end of a bowling pin, said constriction including a plurality of elongated fingers each having a bowling pin engaging end, arms on said housing ver-

tically pivotally attaching said fingers adjacent the smaller end of said housing, said fingers extending radially inwardly of said housing and forming a constriction, pins on said fingers engaging said arms for supporting said fingers in a horizontally disposed position, said fingers being so constructed and arranged to vertically pivot upwardly when the head of a bowling pin is passed therethrough and pivot downwardly into a horizontally disposed position when the neck of a bowling pin is received between said fingers to prevent withdrawal of the pin from the pickup device, and means for selectively vertically pivoting said fingers into their bowling pin releasing position, means yieldingly urging said fingers into their horizontally disposed pin engaging position.

5. A bowling pin pickup device comprising a housing having circumferentially spaced openings therein, a pair of relatively spaced arms attached to said housing adjacent each of said openings and extending radially outwardly therefrom, a bowling pin engaging finger vertically pivotally mounted between each of said pairs of arms, means engaging said fingers to limit downward swinging movement of said fingers below a horizontal position, said fingers being so constructed and arranged to vertically pivot upwardly when the head of a bowling pin is passed therebetween and pivot downwardly into a horizontally disposed position when the neck of a bowling pin is received therebetween, a solenoid carried by said arms, and a plunger actuated by each of said solenoids and engaging one of said fingers to vertically pivot said fingers to their pin release position.

6. A bowling pin pickup device comprising a housing having circumferentially spaced openings therein, a pair of relatively spaced arms attached to said housing adjacent each of said openings and extending radially outwardly therefrom, a bowling pin engaging finger vertically pivotally mounted between each of said pairs of arms, means engaging said fingers to limit downward swinging movement of said fingers below a horizontal position, said fingers being so constructed and arranged to vertically pivot upwardly when the head of a bowling pin is passed therebetween and pivot downwardly into a horizontally disposed position when the neck of a bowling pin is received therebetween, a plurality of U-shaped brackets each having a pair of slots in the web thereof, said slots extending perpendicular to the legs of

said bracket and receiving a pair of said arms, means connecting the ends of said pairs of arms remote from said housing to each other, means securing said connecting means to the bracket, 5 a solenoid disposed between the legs of each of said brackets, and a plunger actuated by said solenoids and engaging said fingers to vertically pivot said fingers into their pin release position.

7. A bowling pin pickup device comprising a 10 housing having circumferentially spaced openings therein, a pair of relatively spaced arms attached to said housing adjacent each of said openings and extending radially outwardly therefrom, a bowling pin engaging finger vertically pivotally mounted between each of said pairs of arms, 15 means engaging said fingers to limit downward swinging movement of said fingers below a horizontal position, said fingers being so constructed and arranged to vertically pivot upwardly when the head of a bowling pin is passed therebetween and pivot downwardly into a horizontally disposed position when the neck of a bowling pin is received therebetween, a plurality of U-shaped brackets each having a pair of slots in the web 20 thereof, said slots extending perpendicular to the legs of said bracket and receiving a pair of said arms, means connecting the ends of said pairs of arms remote from said housing to each other, means securing said connecting means to the bracket, 25 a solenoid disposed between the legs of each of said brackets, and a plunger actuated by said solenoids and engaging said fingers to vertically pivot said fingers into their pin release positions, a leaf spring carried by said means for 30 securing said connecting means to said bracket, said leaf spring engaging said finger and yieldingly urging it into a horizontally disposed position.
